2,545,614

MULTIBEVERAGE VENDING MACHINE

Joseph H. Goldberg, Chicago, Ill., assignor to
Drink-O-Matic Co., Chicago, Ill., a partnership

Application July 18, 1945, Serial No. 605,679

3 Claims. (Cl. 225—21)

1

This invention relates to vending machines capable of dispensing differently flavored carbonated beverages from a single source of carbonated water and different sources of flavoring syrups all cooled by a single unit and admixed and dispensed from separate units to prevent contamination or intermixing of the flavors.

Specifically, this invention deals with a carbonated beverage dispenser having a plurality of mixing and dispensing units, an electric motor-actuator for each unit, paper cup dispensers adjacent each unit, and a separate source of syrup for each unit together with a single carbonator for all of the units and a single refrigerator for the carbonator and all of the sources of syrup whereby selective operation of a motor will dispense a syrup-flavored refrigerated and carbonated drink uncontaminated by other flavors dispensed by the other motors but obtained from the same refrigerated source.

A feature of the machines of this invention is the elimination of springs thereby lowering the torque requirements of the actuating motors.

Another feature of the machines of this invention is the elimination of heretofore-required brakes or stops for the actuating motors by allowing a permissible range of override for the motors without interfering with the sequence of operation.

The machines of this invention are coin-actuated and a drink of the desired flavor is dispensed each time a coin is dropped into the particular receptacle for actuating the motor to dispense the desired drink. Contamination of flavors is eliminated by providing an individual syrup tank, syrup conduit, and mixing and dispensing valve unit for each flavor while utilizing a common refrigerator and carbonator for all flavors.

It is, then, an object of this invention to provide a multi-beverage-dispensing machine in which all possibilities of contaminating one flavor with another have been eliminated.

A still further object of this invention is to provide a beverage dispenser which will selectively vend a drink of a desired flavor from a single source of refrigerated and carbonated water but from a separate source of flavor, so that flavor contamination is eliminated.

A still further object of the invention is to provide an electric motor-actuated beverage vending machine having minimum torque load demands on the motor.

A specific object of the invention is to provide a beverage-dispensing machine wherein a coin-actuated electric motor drives cam and pin means

2

to sequentially dispense a cup, rotate a measuring valve to closed position, open a charged-water valve, dispense a flavored charged water drink into the cup, and dump a measured charge of syrup from the measuring valve for the next drink to be dispensed while allowing for an override of the motor without interfering with the next dispensing operation.

Another specific object of this invention is to provide a multi-drink-dispensing machine wherein in a single refrigerator unit cools charged water and a plurality of different drink flavors.

A still further object of the invention is to provide a drink-dispensing apparatus having a plurality of syrup-measuring, mixing and dispensing units each supplied from a single source of charged water and each having an individual source of flavored syrup.

Other and further objects of the invention will be apparent to those skilled in the art from the following detailed description of the annexed sheets of drawings which, by way of a preferred example, illustrate one embodiment of the invention.

25 On the drawings:

Figure 1 is a front elevational view of the multi-beverage-dispensing machine of this invention having the front cover plate removed.

Figure 2 is a vertical cross-sectional view taken along the line II—II of Figure 1.

Figure 3 is a fragmentary enlarged elevational view taken along the line III—III of Figure 2.

Figure 4 is a fragmentary, broken, vertical cross-sectional view, with parts in elevation, taken substantially along the line IV—IV of Figure 2.

Figure 5 is a vertical cross-sectional view, with parts in elevation, taken along the line V—V of Figure 3.

Figure 6 is a horizontal cross-sectional view, with parts in elevation, taken along the line VI—VI of Figure 5.

Figure 7 is a fragmentary front elevational view taken substantially along the line VII—VII of Figure 2.

Figure 8 is a vertical cross-sectional view taken along the line VIII—VIII of Figure 7.

As shown on the drawings:

In Figures 1 and 2 the machine **10** of this invention is shown mounted in a cabinet **11**. Of course this cabinet has a front wall (not shown) covering the apparatus in the cabinet.

A mechanical refrigerator **12** of the compressor-condenser-evaporator type has the compressor and condenser thereof mounted in the

bottom of the cabinet. An electric motor-driven water pump 13 is also mounted in the bottom of the cabinet and receives water from a pipe 14 to pump the water through a pipe 15 into the top of a filter 16. The filter 16 discharges filtered water through a pipe 17. An insulated brine tank 18 is mounted in the cabinet 11 and extends completely across the width of the cabinet as shown in Figure 1. A coil 19 is provided in the brine tank 18 and receives water from the pipe 17. The coil 19 discharges into a carbonator 20. This carbonator can be of any suitable known construction but is preferably of the type disclosed and claimed in my copending application entitled: "Carbonating Device," U. S. Serial 579,097, filed February 21, 1945, now Patent No. 2,402,132, granted June 18, 1946.

A carbon dioxide-containing tank 21 is mounted on the back of the cabinet 11 on a suitable bracket as shown in Figure 2, and discharges CO₂ gas through a tube 22 into the carbonator 20. Carbonated water from the carbonator 20 is discharged through a pipe 23 having branches 23a communicating with two mixing and dispensing units 24. While two such units are disclosed, it should be understood that any number of units can be used.

Two separate syrup tanks 25 and 26 are mounted in the brine tank 18 and each syrup tank has its own separate drain line 27 communicating with a mixing and dispensing unit 24. In this manner, while a single carbonator 20 supplies charged water to both of the units 24, each unit has its own syrup tank and syrup feed pipe so that contamination of flavors is not possible.

A cold plate or evaporator unit 28 is mounted in the brine tank 18 and is connected through tubes 29 with the rest of the refrigerator apparatus 12 in the bottom of the cabinet for circulation of refrigerant. The cold plate 28 cools the brine in the tank 18 of simultaneously refrigerate water in the coil 19, charged water in the carbonator 20, and syrup in the tanks 25 and 26.

As shown in Figure 1, each mixing and dispensing unit 24 has an electric motor 30 associated therewith. Paper cup dispensers 31 and 32 are mounted on each side of each motor 30.

As shown in Figure 5, the motor 30 has a reduction gear housing 30a depending therefrom driving a pinion 33 at about a 25-to-1 speed reduction. A spindle bolt 34 is carried by a bracket 35 on the front face of the brine tank 18 and rotatably supports a gear 36 meshed with the pinion 33. This gear 36 drives a sleeve 37 on the spindle to rotate a vertical cam 38 for a purpose to be more fully hereinafter described.

As shown in Figures 6 and 7, the gear 36 has a pin or lug 39 projecting from the rear face thereof at adjacent the periphery of the gear. A bell crank 40 is pivoted on the cup dispenser 31 and has a depending leg slidably pinned to the dispenser actuator 31a. The other arm of the bell crank 40 extends behind the gear 36 and has an abutment portion 40a thereon lying in the path of the pin 39. An inclined shoe 40b is formed on the end of this arm of the bell crank in spaced relation from the abutment 40a.

The cup dispenser 32 has a similar bell crank 41 pivoted thereon with a depending leg slidably pinned to the dispenser actuator 32a and with the other leg thereof overlying the back face of the gear 36 and having an abutment 41a thereon together with an inclined shoe 41b in spaced relation from the abutment 40a.

The motor 30 drives the gear 36 in the direc-

tion shown by the arrow in Figure 7, thereby causing the pin 39 to engage the abutment 41a of the bell crank 41 and tilt the bell crank to the position illustrated in dotted lines. This tilting of the bell crank slides the cup dispenser actuator 32a to its cup-releasing position and the cup C in the bottom of the actuator will drop as illustrated in dotted lines to be guided by fingers F in upright position on a platform P carried by the cabinet to position the cup beneath the dispenser nozzle of the unit 24. Further rotation of the gear 36 moves the pin 39 beyond the abutment 41a and against the inclined shoe 41b to tilt the bell crank back to its initial position thereby returning the actuator 32a to its starting position. When the pin returns the bell crank to its initial position it can clear the top of the shoe 41b, and the shoe will then rest on the spindle bolt 34 as shown in Figure 7. Continued rotation of the gear will next bring the pin 39 into engagement with the abutment 40a of the bell crank 40 for tilting the bell crank to move the cup dispenser actuator 31a to its cup-release position, and further movement of the pin then causes the pin to engage the shoe 40b of the bell crank 40 for returning the bell crank to its initial position.

The cup dispenser actuators 31a and 32a are thus positively driven in both directions by the pin 39 and the conventional spring return for such actuators is eliminated. The cup dispenser actuators are of well-known construction that serve to discharge one cup at a time when the actuators are slidably moved in their slots as shown.

A full revolution of the gear 36 thus results in a discharge of one cup from each dispenser 31 and 32. The dispensers thus alternately supply the unit 24 with cups. The use of two cup dispensers in place of one increases the drink-dispensing capacity for each unit 24.

As shown in Figures 1 and 2, the cabinet 11 is equipped with a drawer D beneath the platforms P to serve as a receptacle in disposing of cups C after individual servings.

As best shown in Figures 1 and 3, each cam 38 has two diametrically opposed lobes 38a projecting radially therefrom and providing leading driving edges 38b. A pin or lug 42 projects forwardly from the front face of the cam 38 at the trailing end of each cam lobe 38a.

A cam follower roller 43 is rotatably mounted in a clevis or yoke 44 carried by the measuring valve 45 of the mixing and dispensing unit 24 as best shown in Figure 8. This yoke 44 has a link bar 46 pivoted thereon and in turn pivoted to a lever 47 extending upwardly in front of the cam 38 and having its upper end pivoted to a pin 48 carried by the bracket plate 35 as shown in Figure 5.

The measuring and dispensing unit 24 shown in Figure 8 is more fully described and claimed in my copending application entitled: "Dispensing Apparatus," U. S. Serial 590,649, filed April 27, 1945, now Patent No. 2,527,250, dated October 24, 1950. The unit 24 includes the measuring valve 45. A guard plate G secured on the unit 24 bottoms a spring S to hold the measuring valve 45 in the housing. A ball bearing B is interposed between the spring S and guard G so that the spring will not interfere with rotation of the valve 45. The valve 45 is thus rotatably mounted in the casing of the unit, and has a measuring chamber M, C, therein receiving syrup from the pipe 27 through a cam-actuated shut-off valve 49.

This valve 49 is normally closed as shown in Figure 8 but is adapted to be opened by a cam 50 in the measuring chamber of the valve 45 which acts on a lever 51 to depress a pin 52 and open the valve 49 against pressure of the spring 53 to permit syrup to flow into the measuring chamber M. C. When this occurs, the outlet opening 55 for the measuring chamber is out of registration with a port 56 so that the measuring chamber is closed. The port 56 communicates with a 10 dump chamber D. C. for receiving the syrup. A valve casing or tube 57 extends across the dump chamber D. C. and receives charged water from the pipe 23a. This tube 57 has a valve seat 57a therein normally closed by a spring-pressed valve 58 having a pin 59 projecting forwardly therefrom out of the front end of the unit 24. A rocker arm 60 overlies the pin 59 and is actuated by a cam roller 61 which engages a cam 62 on the front face of the measuring valve 45. Charged water is discharged, when the valve 58 is opened, into a chamber 63 and drained therefrom through a tube 64 entering the dispenser nozzle 65 for the unit. This nozzle 65 has apertures 66 around the periphery thereof discharging the charged water into a valve carriage 67 having a valve head 68 closing a drain port at the bottom of the dump chamber D. C. A cam 69 on the periphery of the measuring valve 45 acts on a roller 70 to depress a yoke 71 which lowers the valve carriage 67 against the pressure of the spring 72 in the nozzle. The spring 72 acts on a plunger 73 which in turn acts on pins 74 holding the valve carriage 67 in closed position. The cams 62 and 69 open the valves 58 and 68 simultaneously so that the syrup from the dump chamber D. C. and the charged water from the valve chamber 57 are discharged simultaneously along the inner and outer faces of the valve carriage 67 to be mixed and guided by a shield 75 into a cup on the platform P.

The cam 38 driven by the motor 30 is rotated in the direction shown by the arrow in Figure 3 to move a driving edge 38b thereof into engagement with the roller 43 and thereupon rock the measuring valve 45 to cause the cams 62 and 69 thereon to open the charged water valve 58 and the dump valve 68 thereby dispensing a drink containing charged water issuing from the tube 64 and syrup contained in the dump chamber D. C. This rotation of the measuring valve 45 also moves the dump opening 55 thereof out of registration with the port 56 to close the measuring chamber M. C. The cam 50 in this measuring chamber then opens the valve 49 to admit syrup into the measuring chamber for filling the chamber. The cam lobe 38 then passes over the roller 43 as illustrated in dotted lines in Figure 3. When the cam roller is in this dotted line position the lever 47 has been swung over the dotted line position and the pin 42 on the other cam lobe 38 then engages the lever to push it back to the full line position thereby returning the cam roller and rocking the measuring valve 45 back to the position shown in Figure 8. On this return movement of the measuring valve 45 the shut-off valve 49 is closed and the discharge opening 55 of the valve is placed in registration with the port 56 to dump the measured quantity of syrup in the measuring chamber M. C. into the dump chamber D. C. where it is held for dispensing the next drink.

The pin 39 on the gear 36, the driving edges 38b, and the pins 42 on the cam 38 are so positioned that, for each complete revolution of 75

the gear by the driving motor, a cup will be dispensed from one dispenser 31 or 32, a drink will be dispensed from the unit 24, the dispenser actuator will be returned to initial position, and the mechanism in the unit 24 will be returned to its initial position. Then the other cup dispenser will be actuated to release a cup, the unit 24 will be actuated to dispense another drink into the cup, and the cup dispenser and unit will be returned to initial position. During drink dispensing by the unit 24, the measuring valve is receiving a new charge of syrup for the next drink and, as the measuring valve is returned to initial position, this measured charge of syrup is dumped into the dump chamber where it is held until the next drink is dispensed.

Preferably the speed arrangement is such that two seconds are allowed for dispensing a cup; two seconds are allowed for dispensing a drink in the cup; and two seconds are allowed for possible override of the electric motor without interfering with any of the operations or the sequence of operation. In this manner, no brake need be provided on the motor since the two second override period is ample to accommodate any possible coasting of the motor after it has been de-energized. As shown in Figures 1 and 2, suitable electrical relay mechanism is provided in a box 76 in the top of the cabinet. Standard coin-actuated 30 relays can be used.

From the above descriptions it will be understood that the machines of this invention require only a single refrigerator unit and carbonator for dispensing a plurality of differently flavored drinks while eliminating all possibility of contamination of one drink flavor with another. Heretofore-required spring returns and the like spring-actuated mechanisms have been substantially eliminated so that the driving motor need only have relatively low torque load capacity. At the same time, positive driving and return movements are obtained. The cam actuating and pin means for the unit are of simple construction and are directly driven from the electric motor thereby eliminating possible sources of faulty timing due to complicated arrangements.

It will, of course, be understood that various details of construction may be varied through a 50 wide range without departing from the principles of this invention and it is, therefore, not the purpose to limit the patent granted hereon otherwise than necessitated by the scope of the appended claims.

55 I claim as my invention:

1. In a drink dispensing apparatus a valve unit having a rockable measuring valve with a measuring chamber therein, a dump chamber, a charged water valve and a dispensing valve for emptying said dump chamber, an electric motor driven cam having abutment means for rocking said measuring valve, lug means for returning the rocked measuring valve to initial position, and cams on said measuring valve for actuating the charged water valve and the dispensing valve to open said valves when the measuring valve is in rocked position.

2. In a drink dispensing apparatus an electric motor, cam and lug means driven by said electric motor, a cup dispenser, a rocking member actuated by said lug means releasing a cup from said dispenser to move by gravity into position for filling, a mixing and dispensing valve unit including a rotatable measuring valve actuated by said cam means and a dispensing valve actuated by

7
said measuring valve upon turning movement thereof.

3.3. In a drink dispensing apparatus a cam having a driving abutment and a lug in trailing relation to said driving abutment; an electric motor for driving said cam in one direction; and a mixing and dispensing valve including a rotatable measuring valve and an operative connection between said valve and cam and lug to rock said valve in one direction by the driving abutment of said cam and in the opposite direction by said lug.

JOSEPH H. GOLDBERG.
